United States Patent Office.

E. H. BUCKLAND, OF SPRINGFIELD, MASSACHUSETTS.

Letters Patent No. 77,580, dated May 5, 1868.

IMPROVEMENT IN SPRINGS FOR WATCH-CASES.

The Schedule referred to in these Letters Patent and making part of the same.

TO ALL WHOM IT MAY CONCERN:

Be it known that I, E. H. BUCKLAND, of Springfield, Hampden county, Commonwealth of Massachusetts, have invented a new and useful Improvement in "Watches;" and I do hereby declare that the following is a full and clear description thereof, reference being had to the accompanying drawings, and to the letters of reference marked thereon.

Figure 1 represents a sectional view of the rim of a watch-case, and

Figure 2 is a detailed view of a part of my invention, as shown in fig. 1.

This invention consists of an improvement upon my improved arrangement of catch and throw-up spring, for which application for patent was made, February 5, 1868, and is intended to obviate a difficulty arising from the application of my improved spring to some forms of watches.

In my first application, (referred to,) the catch and throw-up spring are formed in one piece, reaching more than half around the inside groove in the case. This spring is shown here in fig. 1, and is applied to an old watch-case where the catch was not in front of the push-pin.

In my former application, the catch was either formed upon the end of the push-pin A, or it was placed upon the spring B itself. When, however, the spring B is to be applied to an old arrangement of push-pin, as here shown, it is necessary that the catch be either formed upon the new spring, or another piece be inserted which can be adjusted to the various situations of the former catches respectively.

The first method is inconvenient, because a separate spring would probably have to be made for each watch repaired by its insertion, and the manufactured springs could not be used, as the catch is formed upon them could not be made to fit every construction of case. The second method, however, I employ, and construct the new piece as follows:

Fig. 2 shows this new piece in detail. It consists of a segment of circular strip, C, conforming in circle or nearly so to the inside circumference of the rim. A catch, D, is formed upon its edge at one end. It is placed between the rim of the case and the spring B, with the catch occupying the position of the former catch, and is, of course, operated by the spring B and push-pin A with precisely the same effect as if it had been formed upon the spring itself at this point.

By this means I completely obviate the difficulty arising from the fact that nearly every old watch-case has its catch-socket cut in the rim at a different point from its next neighbor, and this extra piece is of no more cost in manufacture than would be expended upon the formation of a catch upon the push-pin itself, thus making the application of the single spring B equally convenient for old and new watch-cases.

Now, having described my invention, what I claim as new, and desire to secure by Letters Patent, is—

The independent catch D, formed upon the strip C, in combination with the spring B and push-pin A, substantially as herein described.
